Term of patent 14 years

(Cl. D23—80)

Fig. 2.

Fig. 3.

FIGURE 1 is a perspective view of a base for space heater for orchards and the like showing our new design;

FIGURE 2 is an exploded side elevational view, showing the base in cooperation with a heater stack; and

FIGURE 3 is a sectional view taken on line 3—3 in FIGURE 1.

The dominant features of our design reside in the portions shown in full lines. The fuel spray nozzle and feeder line shown in FIGS. 1 and 3 and the heater stack shown in FIG. 2 are for illustrative purposes only.

We claim:

The ornamental design for a base for space heater for orchards and the like, as shown and described.
